Specification for Design.

Patented Mar. 9, 1920.

Application filed September 13, 1919. Serial No. 321,474. Term of patent 14 years.

To all whom it may concern:

Be it known that I, GEORGE J. RICHARDSON, a citizen of the United States, residing at New York city, county of New York, State of New York, have invented a new, original, and ornamental Design for a Combined Trash-Receptacle and Advertising Medium, of which the following is a specification, reference being had to the accompanying drawing, forming part thereof.

The accompanying drawing represents a combined trash receptacle and advertising medium.

Figure 1 is a perspective view of the combined trash receptacle and advertising medium.

Fig. 2 is a similar view looking from the opposite corner.

I claim:

The ornamental design for a combined trash receptacle and advertising medium as shown.

GEORGE J. RICHARDSON.
